Primary Examiner — Kimberly Barnes

(57) **CLAIM**

The ornamental design for a wall hook for a fire extinguisher, as shown and described.

DESCRIPTION

This application incorporates by reference in its entirety and claims priority from the following applications:

U.S. Ser. No. 29/612,238 filed Jul. 31, 2017, entitled Fire Extinguisher, that issued as U.S. Pat. No. D843,068 on Mar. 12, 2019,

U.S. Ser. No. 29/505,639 filed Dec. 24, 2015, entitled Fire Extinguisher, that issued as U.S. Pat. No. D796,121 on Aug. 29, 2017 and

U.S. Ser. No. 29/526,021 filed May 5, 2015, entitled Fire Extinguisher, that issued as U.S. Pat. No. D777,991 on Jan. 31, 2017.

FIG. 1 is a top front perspective view of a wall hook for a fire extinguisher showing our new design;

FIG. 2 is a top rear perspective view thereof;

FIG. 3 is a bottom view thereof;

FIG. 4 is a top view thereof;

FIG. 5 is a left side view thereof;

FIG. 6 is a right-side view thereof; and,

FIG. 7 is a rear view.

The features shown in broken lines in the figures depict environmental subject matter only and form no part of the claimed design.

1 Claim, 4 Drawing Sheets
